UNITED STATES PATENT OFFICE.

HANS F. RICHTER, OF WINSTON-SALEM, NORTH CAROLINA, ASSIGNOR, BY MESNE ASSIGNMENTS, TO R. J. REYNOLDS TOBACCO COMPANY, OF WINSTON-SALEM, NORTH CAROLINA, A CORPORATION OF NEW JERSEY.

TOBACCO-STEMMING MACHINE.

1,347,404.

Specification of Letters Patent. Patented July 20, 1920.

Application filed July 1, 1916, Serial No. 107,119. Renewed May 12, 1919. Serial No. 296,536.

To all whom it may concern:

Be it known that I, HANS F. RICHTER, of Winston-Salem, in the county of Forsyth and State of North Carolina, have invented 5 certain new and useful Improvements in Tobacco-Stemming Machines, of which the following is a specification.

The present invention relates to an improved tobacco stemming machine having 10 the general characteristics of that disclosed in my companion application for Letters Patent of the United States, Serial No. 93,952, filed April 27, 1916.

The improvements are illustrated in the 15 accompanying drawings, wherein—

Figure 1, is a rear view of so much of the machine as is necessary for an understanding of the present invention. Fig. 2, is a front view. Fig. 3, is a vertical section. 20 Fig. 4, is a detailed cross section in the plane indicated by the line 4—4 in Fig. 3. Fig. 5, is a cross section through the stationary bearings of the gripping rolls. Fig. 6 is a cross section through the leaf conveyer 25 and the knife carrying portion of the gripping rolls.

As in the companion application above referred to, the stemming instrumentalities comprise a traveling leaf conveyer consisting of two endless traveling belts A and B, having yielding faces of wire teeth, and two stem gripping and drawing rolls C and D, with roughened or knurled surfaces to effectively grasp the stems of tobacco leaves 30 and feed them transversely to the travel of the leaves as they are conveyed by the conveyer belts. In this way, the stem gripping rolls draw the stems from the blades of the leaves which are held and conveyed by 35 the conveyer. This action is fully described in the aforesaid companion application.

It occasionally happens that the tobacco leaves have not been separated by the farmer from the stalks of the tobacco plants. 40 In such cases, it sometimes occurs that the thick, tough stalks enter between the separated tapered ends of the stem gripping rolls C and D, and clog, choke or injure the machine. To obviate such clogging or 45 injuring; one of the stem gripping rolls is mounted in a yielding bearing. As shown in the drawing the lower stem gripping roll D, is rotatably mounted at one end in a bearing E. This bearing E is located and

55 maintained in place in a frame F, having on its front side a removable plate G. The bearing E has a limited vertical movement within the frame which is sufficient to permit the stem gripping rolls to separate far enough to accommodate the stalks of tobacco plants but insufficient to permit the disengagement of the driving gears H and I. The bearing E is maintained against end-wise movement within the frame F by means of a fixed pin J, carried by plate G, which 60 enters a vertical slot K, in the bearing E, this slot permitting the vertical movement of the bearing.

The bearing E is maintained uplifted by a stiff spring L. This spring is stiff enough 70 to maintain the lower stem gripping roll D in proper working position with respect to the upper stem gripping roll C during the stemming action; but it yields under the excessive strain due to the entrance of stalks 75 between the stem gripping rolls. As illustrated, the spring L is of rubber. It is located between plates M and N. A bolt O passes through the said plates and the rubber spring and is secured at its upper end to the 80 bottom of the frame F. The plates M and N, and the spring L, are maintained in place by a nut P, by means of which also the tension of the spring can be regulated. Between the upper plate M and the bearing E 85 are two pins Q, which rest on plate M, pass through holes in the bottom of the frame F, and bear against the bottom of the bearing E. Through these pins the pressure of the spring L is transmitted to the bearing E. 90

This yielding apart of the stem gripping rolls not only prevents injury and clogging in the event of plant stalks entering the rolls but also in case any hard foreign matter enters between them. 95

The outer free ends of the tapering stem gripping rolls are separate and open to permit the introduction of the stems. In order that these ends of the stem gripping rolls may be maintained in proper relation to 100 each other without separation due to the strain of the work done, each roll has a cylindrical journal R at its outer end which fits against a curved open thrust bearing S, which is adjustably mounted on the frame 105 work T of the machine. The thrust bearings S not only prevent the separation of the free ends of the stem gripping rolls but

also serve as bearings against which the outer ends of the stem gripping rolls rotate. These thrust bearings are open on their facing sides: That is to say, one bearing R, is above the outer journal of the roller C, and the other thrust bearing R, is below the outer journal of the roller D. Hence no part of the thrust bearings interfere with the entrance of the stems between the rolls and the thrust bearings can be adjusted after said rolls are mounted in the machine.

A portion of the stem near the tip end of the leaf is not objectionable and it is permissible to leave it in the "strip" so as to 15 retain all of the usable part of the leaf. Accordingly, a knife is provided to cut off the stem near the tip end of the leaf. As shown in Figs. 1 and 6, the upper stem gripping roll C has an inserted steel knife U extending parallel with the axis of the roll between the bearing for the roll and the knurled or roughened portion. This knife U co-operates with a soft metal anvil V inserted in the lower stem gripping roll D between its 20 knurled portion and its bearing and so located that when the knife U is at the bottom of the roll C (as shown in Fig. 6) the anvil V is immediately beneath it. Accordingly, when a stem has been fed past the knurled 25 portions of the two stem gripping rolls (as the result of the leaf conveying movements of the conveyer belts) it will be cut off by the conjoint action of the knife U and the anvil V. More than one knife and one anvil 30 may be employed.

The nurling or roughening of the rolls is spirally arranged as illustrated in the drawings so as to have a feeding action on the stems to carry them lengthwise of the 35 rolls concurrently with the withdrawal of the stems from the leaves in a direction at right angles to the length of the rolls as the result of the gripping action of the rolls. The spiral nurling or roughening of the 40 rolls extends throughout their gripping surfaces so that their feeding tendency continues as long as the gripping action lasts.

I claim—

1. A tobacco stemming machine having, 45 in combination, a pair of stem gripping rolls, one of said rolls having a knife and the other an opposing anvil for cutting

across the stems, said knife and anvil being located at the terminus of the gripping surfaces of the rolls, and a traveling leaf conveyer which feeds the leaves and stems lengthwise of the rolls and brings the stems into position to be cut by the knife. 55

2. A tobacco stemming machine having, in combination, a pair of stem gripping rolls, one of said rolls having a knife for cutting across the stems, said knife being located at the terminus of the gripping surfaces of the rolls, and a traveling leaf conveyer which feeds the leaves and stems 60 lengthwise of the rolls and brings the stems into position to be cut by the knife. 65

3. A tobacco stemming machine having, in combination, a traveling leaf conveyer and a pair of stem gripping rolls having knurled or roughened surfaces to enhance 70 their grip upon the stems, the nurling or roughening extending spirally throughout the gripping surfaces of the rolls for the purpose of aiding in feeding the stems 75 lengthwise of the rolls as the leaves are advanced along the rolls by the conveyer.

4. A tobacco stemming machine having, in combination, a pair of stem gripping rolls journaled at their inner ends and having 80 separated and spaced cylindrical ends constituting outer journals for said rolls, and fixed thrust bearings for said cylindrical ends, said bearings being open on their facing sides. 85

5. A tobacco stemming machine having rotating gripping rollers geared together, in combination with a movable bearing for one of said rolls, means for limiting the movement of said bearing so as to prevent disengagement of the gears, a frame in which said movable bearing is mounted, a bolt fastened to one wall of said frame, a plate movable on said bolt, pins extending through the wall of said frame and between said 90 movable plate and said movable bearing, a second plate carried by said bolt in normally fixed position, and a stiff spring surrounding said bolt and interposed between 95 said plates. 100

In witness whereof I have hereunto signed my name.

HANS F. RICHTER.
